11 Claims. (Cl. 74—604)

The present invention relates to devices for imparting impulses to a system. It is more especially, although not exclusively, concerned with devices of this kind for imparting impulses, with a view to at least partly ensuring the balancing of its kinematic cooperating means, to the crank-shaft of an alternating machine, such as an internal combustion engine having its cylinders disposed in fan-like arrangement, with two or more branches, or in simple or multiple radial arrangement, and more especially an engine the kinematic system of which includes the combination of a main connection rod and other connecting rods.

In a prior patent, No. 2,156,484, I described a device for reducing the vibrations of a system including a rotating element, these vibrations being due to a pulsatory force acting on said element and rotating at the same speed of revolution as the element in question, this device including a pendular system constituted by at least two pendulums pivoted to the rotating element on either side of the radial plane containing said pulsatory force and coacting with a device capable of controlling the oscillation of the pendulums on either side of their radial position.

The chief object of the present invention is to provide a device of the type above described which is better adapted to meet the requirements of practice than those used for the same purpose up to the present time, and, in particular, simpler than up to now.

According to an essential feature of the present invention, in order to reduce the vibrations of a system including a rotating element or structure, this system being subjected to the action of a pulsatory force turning at the same rate as this rotating element or structure, I make use, in order to balance this force, of a free pendular system (that is to say a system independent of any control means), this system being carried by said rotary structure and being urged back toward its neutral position merely by the centrifugal force created by the rotation of this structure, this pendular system being constituted by at least two pendulums pivoted to the rotary structure on either side of the radial plane containing said pulsatory force and adapted to oscillate, with their natural frequency, so as to make, for every revolution of the rotary structure, as many complete beats as there are pulsations of the pulsatory force.

Another feature of the present invention relates to the case in which it is desired to reduce the oscillations of a system or assembly includ-

ing a rotary element or structure, this assembly being subjected to the action of a pulsatory force of order n with reference to the rotary structure (that is to say having n pulsations per revolution of the rotary structure) and of a pulsatory torque of the same order, making a certain angle with said force, the latter turning at the same speed as the rotary structure. This feature consists in making use, for balancing both this force and this torque, of a pendular system carried by said rotary structure and urged back toward its neutral position by the centrifugal force created by the rotation of said structure, this pendular system being constituted by at least two pendulums pivoted to the rotary structure on either side of the radial plane containing said pulsatory force and adapted to oscillate, with their natural frequency, about mean positions making an angle different from 90° with the perpendicular to said radial plane, with n beats of the pendulums for every revolution of the rotary structure.

Other features of the present invention will result from the following detailed description of some specific embodiments thereof.

Preferred embodiments of the present invention will be hereinafter described, with reference to the accompanying drawings, given merely by way of example, and in which:

Fig. 1 is a diagrammatical view illustrating the principle of the invention when it is desired to reduce or to compensate a rotary pulsatory force.

Fig. 2 is a diagrammatical view illustrating the principle of the invention when it is desired to reduce both a rotary pulsatory force and a pulsatory torque of the same order making a certain angle with said force;

Fig. 3 is a diagram showing the perturbing forces which are produced in the case of a system including a main connecting rod and at least one other connecting rod associated therewith;

Fig. 4 diagrammatically shows, in end view, the crankshaft and the connecting rod system of a radial engine with a master connecting rod and auxiliary rods associated therewith, this system being provided with balancing means according to the present invention;

Fig. 5 shows, in a manner similar to Fig. 4, a modification of the device according to the present invention;

Fig. 6 is a diagrammatical view showing in perspective a system similar to that of Fig. 5 but including a crankshaft with two opposed crank arms;

Fig. 7 shows, in a manner similar to Fig. 4, a modification of the device illustrated by Fig. 6;

Fig. 8 diagrammatically shows a crankshaft with two opposed crank arms, provided with means made according to the embodiment of Fig. 7;

Finally, Fig. 9 shows, in a manner similar to Fig. 4, a modification of the device according to Fig. 7.

According to the invention, it is desired to provide a device for imparting impulses to a system including a rotary structure, for instance a crankshaft, with a view to compensating, at least partly, for a rotary pulsatory force of order n , that is to say having n periods for every revolution of the rotary structure v (see Fig. 1) and carried by a radial vector OX which turns together with the rotary structure about the axis O thereof.

I make use of at least one pendular system which is carried by said rotary structure or by an element associated with said structure, this system including, on either side of the radial plane OX , two free pendulums p, p' urged back toward their neutral position merely by the centrifugal force created by the rotation of this element, these pendulums being arranged in such manner as to oscillate in planes at right angles to the axis O of rotation of the rotary structure and having a natural frequency of order n , that is to say having, same as the rotary pulsatory force, n periods per revolution of the rotary structure.

The axes of articulation l and l' of pendulums p and p' , which are parallel to axis O , will be located preferably in symmetrical relation with reference to axis O in a plane DD' perpendicular to vector OX and passing preferably through said axis.

When such a system is in operation, it is found that these pendulums assume by themselves movements such that they remain constantly out of phase with respect to each other by one half of a period, that is to say that they remain always, at a given time, on the same side of plane DD' .

Considering then these pendulums when they pass through their positions corresponding to the maximum of the angles they make with their positions of equilibrium (position shown by the drawings), it is found that these forces are two forces F and F' symmetrical with respect to OX so that their projections on this direction will be added to each other at any time in absolute value, the resultant of these projections being a pulsatory force of the same period as said pendulums.

Therefore, it will be readily understood that it is possible, by suitably choosing the masses of pendulums p and p' , to arrange that this resultant is constantly substantially equal in intensity and opposed in direction to the perturbing pulsatory force to be compensated.

In the device according to Fig. 1, the two pendulums p and p' are connected together through suitable means, for instance connecting rods 14 pivoted to fingers carried by the pendulums, said connecting means compelling the pendulums to oscillate with the desired de-phasing with respect to each other, but it should be noted that these connecting means are not at all necessary.

In the device according to Fig. 2, the axes of articulation l, l' of pendulums p, p' , instead of being located in a plane passing through axis O , are located in a plane $Da-Da'$ perpendicular to vector OX and located at a certain distance from axis O . The radii passing respectively through the axes of articulation of the two pendulums, on the one hand, and through the axis 75

of rotation of the rotary structure, on the other hand, make with each other an angle different from 180° so that the pendulums do not only communicate to rotary structure v a pulsatory radial force of order n , but also a pulsatory torque of the same order, with a dephasing of a certain angle with respect to said force and coaxial with said rotating element or structure v , said force and said torque being capable of simultaneously compensating a perturbing force and a corresponding perturbing torque.

The dephasing between the rotating pulsatory force and the pulsatory torque determines the angle between radii Ol and Ol' , or angle θ , the latter being the angle made respectively between said radii and the plane DD' passing through axis O , respectively. When the dephasing between the pulsations of the rotary force and the torque is equal to 90° , angle θ is preferably equal to 45° , which permits of obtaining the most accurate results.

If, in the embodiment according to Fig. 2, the rotary structure v is subjected simultaneously to the action of a rotating pulsatory perturbing force and a pulsatory torque, of the same frequency as said force but shifted in phase with respect to the latter, pendulums p and p' are automatically set into oscillation, with a dephasing of 180° more or less an angle ϕ for thus creating the compensating force and the compensating torque.

It has been supposed, for the sake of simplicity, that the compensating pendulums were of the monofilar type, but obviously this is not a necessary condition and, in particular, these pendulums might be of the bifilar type, this arrangement permitting, in particular, of reducing the length of the pendulums as much as it may be necessary for practical purposes for obtaining high natural frequencies of said pendulums.

A particularly interesting application of the invention consists in absorbing the oscillations which occur in a radial cylinder including a system of connecting rods constituted by a master connecting rod with a head 3 to which the heads of connecting rods 4 are pivoted about axes 5 distinct from the axis of crank pin 6 (see Figs. 4 to 9).

It is known that such a system applies to the crank pin a force F (Fig. 3) of constant value, making with the crank radius an angle α equal to, and in the same direction as, the angle made by said crank radius with the axis $O'X'$ on which moves the other end of the master connecting rod. This is true if said axis is radial and very close to the truth in the other cases which are practically met with.

This force F may be decomposed into two other forces, one of which is a radial force $F \cos \alpha$ and the other a force perpendicular to the crank radius, to wit, $F \sin \alpha$.

The first mentioned force is a radial pulsatory force carried by vector $O'X'$, which turns together with the crankshaft, with the same speed as the latter, and is of a frequency equal to the speed of revolution of the crankshaft, that is to say of order 1, whereas the other force produces a pulsatory torque of axis O' and also of order 1 with respect to the speed of revolution of the crankshaft, this torque being dephased by 90° with respect to the force. In order simultaneously to compensate for said pulsatory force and said pulsatory torque, I provide on the crankshaft a pendulum system the pendular

movements of which are produced and maintained exclusively by the effect of said perturbations on the crankshaft.

According to the embodiment illustrated by Fig. 4, I provide, in order to reduce the perturbing pulsatory force of order 1, two pendulums p, p' pivoted to the crankshaft about axes l and l' , these axes being located in a plane DD' perpendicular to vector $O'X'$ and passing preferably through axis O' . The natural frequency 10 of pendulums p, p' is chosen in such manner that they make a complete oscillation for every revolution of the crankshaft. Pendulums p, p' impart to the crankshaft a compensating force which is substantially equal and opposed to the rotary force $F \cos \alpha$ whereby these two forces mutually destroy each other, at least substantially.

In order to reduce the perturbing pulsatory torque, I have recourse, according to Fig. 4, to 20 a single pendulum, pivoted to the crankshaft on the side of the crank pin, this pendulum being preferably mounted in such manner as to oscillate about the very axis of the crank pin, for which purpose it is advantageously made of the bifilar form, its mass 15 being suspended through two connecting rods 16 and 17 to two axes carried on either side of one of the cheeks of the crank pin.

The natural frequency of this last mentioned 30 pendulum is also of order 1 with respect to the speed of the crankshaft.

Of course, the mass of this last mentioned pendulum is balanced by a suitable increase of the mass of the usual counterweight of the 35 crank pin.

This embodiment constitutes an accurate solution of the problem, but its application to engines of the usual types produces, in some cases, difficulties which are chiefly due to the lack of room for housing, on the one hand, the third pendulum 15, and, on the other hand, the normal counterweight, the size of which is to be increased so as to balance the mass of the pendulum in question.

In order to avoid this difficulty, I pivot, in the arrangement according to Fig. 5, said third pendulum to the crank shaft at a point located on the other side from the crank pin with respect to the axis of revolution of the crankshaft.

Of course, such a pendulum system leaves certain reactions acting on the supports of the engine but these reactions are not disturbing from a practical point of view.

The device which has just been described has the advantage that it is possible to utilise, for constituting the mass of pendulum 18, the usual counterweight which must be provided in connection with the crank pin. As a matter of fact, it suffices to suspend this counterweight, for instance through a bifilar suspension, to one of the crank arms 9 of the crankshaft.

As for pendulums p and p' , they may be merely pivoted in fork-shaped parts provided on the sides of the same crank arm or of another crank arm. It should be noted that, if the plane DD' passing through their axis of articulation also passes through axis O , the presence of pendulums p, p' does not necessitate any modification of the mass of the usual counterweight, therefore of the mass of pendulum 18.

When the crankshaft is to include, in addition to the pendular system which has just been described, a device for damping torsional vibrations constituted, for instance, by a second pendular

system the natural frequency of which corresponds, for every revolution of the crankshaft, to a number n of complete oscillations equal to one half of the number of cylinders, the first pendular system may be carried by a crank arm and the second by another crank arm.

This may be the case as well when the crankshaft has a single bend as when it has several bends.

In the second case, the pendular system made according to the invention, instead of partly balancing the force P above mentioned, partly balances the torque constituted by the two forces F , equal and of opposed directions, created by the two systems of connecting rods, including a master connecting rod and a plurality of auxiliary rods.

Thus, although it is possible to make use of a distinct pendular system for each bend of the crankshaft, it is also possible, as shown by Fig. 6, to utilize only a single pendular system of order 1 for the whole of the crankshaft.

It is then advantageous to mount this system on the front crank arm of the crankshaft, on the side of propeller 19, whereas the pendular system 20 of order n' is mounted on the rear crank arm.

According to another embodiment of the invention (Figs. 7 to 9) which is also more particularly applicable to the case of a system including a master connecting rod and at least one secondary rod, I make use of an arrangement similar to that diagrammatically shown by Fig. 2 for compensating simultaneously, and by means of only two pendulums, as well the pulsatory radial perturbing force as the pulsatory perturbing torque. In order to obtain this result, I pivot the pendulums p and p' above described about axes l and l' preferably located in a plane Da, Da' perpendicular to vector $O'X'$ but, in this case, instead of having this plane Da, Da' passing through the axis O' , it is located at a distance therefrom, whereby the planes passing respectively through axis O' and the two axes l, l' both make an angle equal to θ with the plane passing through axis O' perpendicularly to vector $O'X'$ (Fig. 7) which angle can, in every case, be determined by calculation.

By way of example, it may be noted that, in order to obtain this result, it is necessary, in the case of a crankshaft having a single bend for a system including a master connecting rod and a secondary rod, to comply approximately with the following condition:

$$a = R \sin \theta$$

in which:

a is the distance of axes l and l' from axis O ; R is the eccentricity of the crank pin; and θ is the angle above defined, this angle being preferably equal to 90° .

In the case of a symmetrical crankshaft with two bends provided with pendular systems merely on its extreme crank arms, the relation between a and θ (preferably equal to 90°) must be:

$$a = \frac{b+c}{b} R \sin \theta$$

in which:

b is the distance between the middle point of a crank pin and the center of the crankshaft (Fig. 8) and c is the distance between each of the planes in which the compensating pendulums are moving and the middle of the corresponding crank pin.

Of course, instead of two pendulums the axes of which are disposed along planes making an angle

θ upwardly with the plane normal to vector $O'X'$ and passing through O' , I might use several sets of such pendulums, for instance two sets for which the respective angles θ would be turned upwardly for one set and downwardly for the other.

In other words, instead of two pendulums at 45° in the upward direction with reference to $O'X'$ (Fig. 7) I might utilize four at right angles to one another and each at 45° with respect to $O'X'$.

One might also have recourse to any other suitable arrangement, for instance utilize, either 6 pendulums at 60° to one another (four of them being at 30° to $O'X'$), or 8 pendulums at 45° to one another.

In all cases, if the crankshaft has a single bend (radial engine with a single row), the pendular systems are placed either on only one crank arm (that located farther from the fixation of the engine to its frame) or on two crank arms, which is the solution which, theoretically, is the best.

If the crankshaft has two bends (double row engines) although it is possible to provide two pendular systems identical to each other and located on either side of each crank pin, it will be simpler to provide only two pendular systems by providing them on the end crank arms of the crankshaft (Fig. 8).

It will be readily understood that, in this case, the displacements of the pendulums which are opposed to the two pulsatory torques at 180° to each other produce a periodical twisting of the shaft.

But it happens that the pendulums which oppose the two pulsatory forces at 180° to each other can oppose this periodic twisting.

It suffices for this purpose to have them dephased by an angle ϕ (of a nature analogous to the angle α above referred to) which angle is automatically produced in view of the fact that the pendulums are wholly free to oscillate in response to the vibratory displacements of their points of suspension.

Of course, the compensating pendulums might be carried by parts other than the crank arms of the crankshaft and in particular by all suitable supports fixed thereon.

In the preceding description, the pendulums have been considered as being in the form of masses pivoting with respect to the rotary structure, but of course it would be possible, and in some cases advantageous, to constitute them by fluid masses, for instance mercury masses, contained in vessels of suitable shape.

For instance, according to the embodiment illustrated by Fig. 9, each of the crank arms 9 of crankshaft v carries two pieces on the inside of each of which there is provided a chamber at least a portion of which corresponds to a volume of revolution about one of the axes l, l' above referred to in the description of Fig. 7.

Thus, if the various characteristics and dimensions of said portion are suitably determined and if a suitable mass of mercury is placed therein, it will be understood that, under the effect of the centrifugal force and of the perturbing vibrations, the displacements of said mass of mercury can produce, on the crankshaft, reactions identical to those produced, under the same circumstances, by the pendulums p_1, p' of Fig. 7.

Preferably, the chambers intended to receive the mass of mercury are given a closed outline so that the mercury does not undergo the action of any return force due to a pressure of the air or gas contained in said chambers.

Likewise, in the whole portion in which the mercury is to move during the pendular movements which take place in the course of the operation, it will be advantageous to provide partitions of revolution about axes l, l' , these partitions being intended to guide the mass of mercury along suitable curves and to avoid the disturbances which might otherwise be produced under certain conditions.

10 These partitions will be advantageously provided with holes which however enable the mercury to be regularly distributed on either side thereof.

They might of course be replaced by a nest of tubes the mean lines of which would be curved in the form of circular arcs having their center on axes l and l' .

Thus, I obtain in any case a radial engine in which the perturbing effects on the crankshaft 20 are for a considerable part compensated, therefore an engine the frame and accessories of which are practically protected against any injurious vibration as might act on the fixation parts of said engine or on the machine, such for instance as an airplane, which carries said engine.

25 Anyway, whatever be the type of engine in connection with which the means above described are employed, these means have many considerable and true advantages, among which the following may be cited:

30 The device can easily be adapted to the compensation of any periodic perturbing factor;

Said device is strong and simple, and therefore reliable in its operation;

35 The space it occupies and its weight are reduced as a consequence of the importance of the centrifugal field acting on the pendulums;

Finally, this device automatically adapts itself to all working conditions of the engine, due to the 40 fact that the natural period of the pendular systems is a function of the centrifugal acceleration, and therefore of the speed of the engine, which is tantamount to saying that, if these systems are arranged in such manner as to make, for instance, a complete oscillation per revolution under given conditions, they will make an oscillation per revolution under all other conditions.

45 It will be readily understood that the invention above described may receive many other applications. For instance it might be employed for damping the perturbing effects to which is subjected a part turning at a given speed by a pendular system carried by a shaft turning at a different speed.

50 55 Of course, in a general manner the invention is not in any way limited to the above described embodiments.

What I claim is:

1. In connection with an assembly including a rotary structure, said assembly being submitted to periodical impulses corresponding to a pulsatory force of order n directed along a radius of said rotary structure, a balancing device which comprises, in combination, two pendular systems eccentrically pivoted to said rotary structure so as to rotate therewith at the mean speed thereof and so as to be able to oscillate about axes parallel to the axis of said structure and situated on either side of the radial plane containing said radius, said pendular systems including each a pendular mass and pendular connecting means between said mass and said rotary structure, said means being the sole force transmitting instrumentality between said mass and said structure. 60 65 70 75 and the natural frequency of said pendular sys-

tems when the angular velocity of the rotary structure is Ω being substantially equal to the product of n by Ω .

2. In connection with an assembly comprising a rotary structure, said assembly being submitted to periodical impulses corresponding to a pulsatory force of order n directed along a radius of said rotary structure, a balancing device which comprises, in combination, two pendular systems eccentrically pivoted to said rotary structure so as to rotate therewith at the mean speed thereof and so as to be able to oscillate about axes parallel to the axis of said structure and symmetrically situated relatively to a radial plane containing said radius, said pendular systems including each a pendular mass and pendular connecting means between said mass and said rotary structure, said means being the sole force transmitting instrumentality between said mass and said structure, and the natural frequency of said pendular system when the angular velocity of the rotary structure is Ω being substantially equal to the product of n by Ω .

3. In connection with an assembly comprising a rotary structure, said assembly being submitted to periodical impulses corresponding to a pulsatory force of order n directed along a radius of said rotary structure, a balancing device which comprises, in combination, two pendular systems eccentrically pivoted to said rotary structure so as to rotate therewith at the mean speed thereof and so as to be able to oscillate about axes parallel to the axis of said structure and situated, on either side of the radial plane containing said radius, in a plane normal to said radius and passing through the axis of rotation of said structure, said pendular systems including each a pendular mass and pendular connecting means between said mass and said structure, said means being the sole force transmitting instrumentality between said mass and said structure and the natural frequency of said pendular systems when the angular velocity of the rotary structure is Ω being substantially equal to the product of n by Ω .

4. In connection with an assembly comprising a rotary structure, said assembly being submitted to periodical impulses corresponding to a pulsatory force of order n directed along a radius of said rotary structure and to a pulsatory torque of the same order but shifted in phase with respect to said pulsatory force, said torque being located in a plane perpendicular to the axis of said rotary structure, a balancing device which comprises, in combination, two pendular systems eccentrically pivoted to said rotary structure so as to rotate therewith at the mean speed thereof, and so as to be able to oscillate about axes parallel to the axis of said structure and situated on either side of the radial plane containing said radius, in a plane normal to said radius and having a distance from the axis of rotation of said structure, and the natural frequency of said pendular systems when the angular velocity of the rotary structure is Ω being substantially equal to the product of n by Ω .

5. In connection with an engine comprising a crankshaft having a crankpin, a master connecting rod associated with said crankshaft, and at least one auxiliary rod, a balancing device which comprises, in combination, two pendular systems eccentrically pivoted to said crankshaft so as to rotate therewith at the mean speed thereof and so as to be able to oscillate about axes parallel to the axis of said crankshaft and situated on either side of the radial plane containing the axis of

the crankpin, said pendular systems including each a pendular mass and pendular connecting means between said mass and said rotary structure, said means being the sole force transmitting instrumentality between said mass and said structure, and the natural frequency of said pendular systems corresponding substantially to one complete oscillation per revolution of the crankshaft.

6. In connection with an engine comprising 10 radially disposed cylinders and pistons therein, a crankshaft having a crank pin, a master connecting rod associated with said crankpin and at least one auxiliary rod, a balancing device which comprises, in combination, two pendular

15 systems eccentrically pivoted to said crankshaft so as to rotate therewith at the mean speed thereof and so as to be able to oscillate about axes parallel to the axis of said crankshaft, and situated, on either side of the radial plane containing the axis of the crank pin, in a plane

20 normal to said radial plane and having a distance from the rotating axis of said crankshaft, and the natural frequency of said pendular system corresponding substantially to one complete oscillation per revolution of the crankshaft.

25 7. In connection with an engine comprising radially disposed cylinders and pistons therein, a crankshaft having a crank pin, a master connecting rod associated with said crank pin and at least one auxiliary rod, a balancing device

30 which comprises, in combination, three pendular systems eccentrically pivoted to said crankshaft so as to rotate therewith at the mean speed thereof and so as to be able to oscillate about three axes parallel to the axis of said crankshaft, the axes of two of said pendular systems being symmetrically situated on either side of the radial plane containing the axis of the crank pin, said pendular systems including each a pendular mass and pendular connecting means

35 between said mass and said crankshaft, said means being the sole force transmitting instrumentality between said mass and said structure, and the natural frequency of said pendular systems corresponding substantially to one complete oscillation per revolution of the crankshaft.

40 8. A device according to claim 4 in which, for a phase difference of 90° between the pulsatory force and the pulsatory torque, each of the planes 50 passing respectively through the oscillation axis of each of said pendular systems on the one hand, and the rotation axis of the rotary structure on the other hand, makes with a plane perpendicular to the vector of the rotary force and 55 passing through the rotation axis of the rotary structure an angle of 45° .

45 9. In connection with an engine comprising radially disposed cylinders and pistons therein, a crankshaft having a crank pin, a master connecting rod associated with said crank pin and at least one auxiliary rod, a balancing device which comprises, in combination, three pendular systems eccentrically pivoted to said crankshaft so as to rotate therewith at the mean speed thereof and so as to be able to oscillate about three axes parallel to the axis of said crankshaft, the axes of two of said pendular systems being symmetrically situated on either side of the radial plane containing the axis of the crank pin, and the third pendular system, of the bifilar type, being located on the other side of the axis of the crankshaft from said crank pin and forming at least a portion of the counterweight, said

60 pendular systems including each a pendular 65 system eccentrically pivoted to said crankshaft so as to rotate therewith at the mean speed thereof and so as to be able to oscillate about axes parallel to the axis of said crankshaft, the axes of two of said pendular systems being symmetrically situated on either side of the radial plane containing the axis of the crank pin, and the third pendular system, of the bifilar type, being located on the other side of the axis of the crankshaft from said crank pin and forming at least a portion of the counterweight, said

70 75 pendular systems including each a pendular

mass and pendular connecting means between said mass and said crankshaft, said means being the sole force transmitting instrumentality between said mass and said structure, and the natural frequency of said pendular system corresponding substantially to one complete oscillation per revolution of the crankshaft.

10. In connection with an engine comprising radially disposed cylinders and pistons therein, a crankshaft having two crank webs, a crank pin, a master connecting rod associated with said crank pin and at least one auxiliary rod, two balancing devices according to claim 7, one of said devices being of order 1 and associated with the front crank web, the other of said devices being of higher order and mounted on the rear crank web so as to damp the torsional oscillations of the crankshaft.

11. In connection with an engine comprising a crankshaft having a crank pin, a master connecting rod associated with said crankshaft, and at least one auxiliary rod, a balancing device

which comprises, in combination, two pendular systems eccentrically pivoted to said crankshaft so as to rotate therewith at the mean speed thereof and so as to be able to oscillate about axes parallel to the axis of the crankshaft and located on either side of the radial plane containing the axis of the crank pin, the planes passing respectively through the axes of said two pendular systems and through the axis of the crankshaft being inclined at 45° to a plane perpendicular to a rotating pulsatory radial force produced by the perturbing action of the connecting rods and passing through the axis of the crankshaft, said pendular systems including each a pendular mass and pendular connecting means between said mass and said structure, said means being the sole force transmitting instrumentality between said mass and said structure, and the natural frequency of said pendular systems corresponding substantially to one complete oscillation per revolution of the crankshaft.

RAOUL ROLAND RAYMOND SARAZIN.
